MAZE PUZZLE

Albert Stubbmann, Franklin Lakes, N.J., assignor to
General Foods Corporation, White Plains, N.Y.

Filed July 2, 1971, Ser. No. 159,588

Term of patent 14 years

Int. Cl. D21—01

U.S. Cl. D34—15 M

FIG. 1

FIG. 2

FIG. 3

FIG. 4

FIG. 5

FIG. 6

FIG. 1 is a top plan view of a maze puzzle in accordance with my invention;

FIG. 2 is a front elevation view thereof, the opposite side being a mirror image thereof;

FIG. 3 is a bottom plan view thereof;

FIG. 4 is a side elevation view thereof, the opposite side being a mirror image thereof;

FIG. 5 is a side elevation sectional view taken along line 5—5 of FIG. 1; and

FIG. 6 is a front end elevation sectional view taken along line 6—6 of FIG. 1.

I claim:

The ornamental design for a maze puzzle, as shown.
